UNITED STATES PATENT OFFICE

123,704

DESIGN FOR A GLIDER END FRAME

William I. Smith, Goshen, Ind., assignor to The Hettrick Manufacturing Company, Toledo, Ohio, a corporation of Ohio

Application September 5, 1940, Serial No. 94,813

Term of patent 14 years

To all whom it may concern:

Be it known that I, William I. Smith, a citizen of the United States and a resident of Goshen, Elkhart County, Indiana, have invented a new, original, and ornamental Design for a Glider End Frame, of which the following is a specification, reference being had to the accompanying drawing, forming a part thereof.

Figure 1 is an end elevational view of the glider end frame, showing my new design; and

Figure 2 is a transverse sectional view on the line 2—2 of Figure 1.

The characteristic feature of my glider end frame design resides in the specific centrally defined end panel in combination with the embossed trim members, and its relation to and association with the frame member, all as shown.

I claim:

The ornamental design for a glider end frame, as shown and described.

WILLIAM I. SMITH.
